ELECTRIC SHAVER

John Hays Hammond, Jr., Gloucester, Mass.

Application July 6, 1938, Serial No. 217,643

7 Claims. (Cl. 30—43)

This invention relates to electric shavers of the type having an outer comb member provided with apertures through which the hairs extend and an inner vibrating or rotating cutter member which cooperates therewith.

An object of the invention is to provide a shaver of the above type having novel and improved operating characteristics.

Various other objects and advantages will be apparent as the nature of the invention is more fully disclosed.

Although the novel features which are believed to be characteristic of this invention will be particularly pointed out in the claims appended hereto, the invention itself may be better understood by referring to the following description, taken in connection with the accompanying drawings, in which certain specific embodiments thereof have been set forth for purposes of illustration.

In the drawings:

Fig. 1 is a fragmentary front elevation, partly in section, of an electric shaver head embodying the present invention;

Fig. 2 is a section through the shaver taken on the line 2—2 of Fig. 1;

Fig. 3 is a fragmentary section taken on the line 3—3 of Fig. 1;

Fig. 4 is a fragmentary front elevation, partly in section, of a modified form of the invention;

Fig. 5 is a section taken on line 5—5 of Fig. 4;

Fig. 6 is a fragmentary front elevation, partly in section, of another modified form of the invention; and

Fig. 7 is a section taken on line 7—7 of Fig. 6.

In the following description and in the claims certain specific terms are used for convenience in referring to various details of the invention. These terms, however, are to be given as broad an interpretation as the state of the art will permit.

Referring to the drawings and more particularly to Figs. 1 to 3, the invention is shown as applied to an electric shaver having a housing 11 which may be made of suitable insulating material, preferably of a plastic composition such as a phenol condensation product. The housing 11 contains a motor 12 which may be of any convenient type. This motor, for example, may be of the brush type or may be of the make-and-break type. In any event, the motor is suitably supported within the housing 11 and drives a shaft 13 which extends longitudinally of the cutter and carries a head 14 which, by means of a connecting rod 15, drives a blade holder 16, which

is rotatably mounted on a shaft 17. A cutting blade 18 is positioned in the blade holder 16 and may be pressed against a semicircular comb 20 by means of a spring not shown. This comb 20 may be provided with a plurality of apertures 21 through which the individual bristles of the beard are adapted to extend. The apertures 21 are shown as circular in form. It is to be understood, however, that these apertures may take the form of elongated slots which may extend either axially or peripherally of the comb or may comprise a combination of round apertures adapted to receive individual hairs and elongated slots through which one or more hairs may extend. The elongated slots may, in certain instances, provide means for cutting hairs which are too long to extend through the round apertures. These features, however, are well known in the art and are accordingly not shown in detail in the drawings.

In the embodiment shown, the comb 20 is circular in section and is attached to end brackets 22 which are pivotally mounted on the shaft 17 and are adapted to permit a limited amount of rotational movement of the comb. One of the brackets 22 is shown as provided with an arm 24 which extends downwardly therefrom and is provided at its end with an elongated slot 25 which is engaged by pin 26 carried by a rotating head 27. The head 27 is mounted on a shaft 28 which carries a worm gear 29, driven by a suitable worm 30 which is mounted on the shaft 13 and is rotated by the motor 12, the arrangement being such that rotation of the head 27 causes 35 an oscillating movement of the arm 24 and of the comb 20.

In the operation of this device, rotation of the motor 12 drives the shaft 13 and, through the head 14 and connecting rod 15, causes the cutting blade 18 to oscillate at a comparatively rapid rate. Rotation of the shaft 13, through the worm 30 and the worm gear 29, drives the arm 24 and causes the comb 20 to oscillate at a slower rate of speed. This oscillation of the comb 20 causes the apertures 21 to be shifted over the beard in such a way that the various hairs are caused to extend therethrough. In this way a clean and uniform cut is obtained with a minimum number of manual strokes. It is to be understood that the various apertures 21 are offset so as to engage a maximum number of hairs at each operation. This, in combination with the oscillation of the comb, produces a satisfactory shave with a minimum amount of effort on the part of the operator.

Referring to the modified form of the invention shown in Figs. 4 and 5 the general construction of the electric shaver is similar to that shown in Figs. 1 to 3 up to and including the comb 20. In this embodiment of the invention, however, the comb 20 is attached to end brackets 35 which are slidably mounted on the rod 17 and on the lower ends of which are mounted pins 36. These pins engage slots 37 provided in two arms 38 which are pivotally mounted on a bracket 39. The two arms 38 are also provided with elongated slots 40 which are engaged by two pins 41 carried by two rotating heads 42. The heads 42 are mounted on a shaft 43 which carries a worm gear 45. The worm gear 45 is driven by a worm 46 which is mounted on the shaft 13 of the motor 12.

In the operation of the modified form of the invention shown in Figs. 4 and 5, the motor 12 drives the cutting blade as already described and also the worm 46 which, by means of the worm gear 45 and shaft 43, causes rotation of the heads 42 and pins 41. This in turn causes an oscillation of the arms 38 which by means of the pins 36 causes an up and down motion of the brackets 35 and comb 20. In this way the comb 20 vibrates in a plane substantially perpendicular to the surface of the skin thus facilitating the entrance of the hairs into the apertures 21 and also causing the comb 20 to be pressed against the skin in such a way that the hairs will be clipped very close to the surface of the skin giving an extremely close shave.

Referring to the form of the invention shown in Figs. 6 and 7 a housing 50 is shown in which is mounted a motor 51 provided with a shaft 52. Secured to one end of this shaft is an eccentric 53 which engages a slot 55 in an arm 56. The arm 56 is secured to a sleeve 57 which is rotatably mounted on a shaft 58 which in turn is rotatably mounted in the housing 50. Secured to the sleeve 57 is a second arm 59 the upper end of which engages a cutter 60 provided with suitable slots 61. The cutter 60 is slidably mounted in a comb 62 which is provided with slots 63. The comb 62 forms part of a D shaped member 65 which is slidably mounted for up and down motion in slots 66 provided in the housing 50.

Two rods 67 are provided with collars 68 and fit loosely in holes in the member 65. The upper ends of the rods 67 are pressed against the under side of the cutter 60 by means of compression springs 69 mounted between the collars 68 and the member 65 and tend to hold the cutter 60 against the comb 62.

Secured to the other end of the shaft 52 of the motor 51 is a pinion 71 which meshes with a gear 72. The gear 72 is secured to the shaft 58 to which is fastened an eccentric 73. This eccentric rotates in a slot 75 provided in the member 65.

In the operation of the modified form of the invention shown in Figs. 6 and 7 the motor 51 rotates the eccentric 53 which imparts an oscillatory motion to the arm 56 and, by means of the sleeve 57, to the arm 59. This motion is transmitted to the cutter 60 which slides rapidly back and forth in the comb 62, thus clipping the hairs of the beard which project through the apertures 63 in a manner well known in the art.

The motor 51 also rotates the pinion 71 and, by means of the gear 72, imparts a less rapid rotary motion to the eccentric 73. The rotation of the eccentric 73 causes the member 65 to move

up and down in the slots 66 thus giving a vibratory motion to the comb 62 and cutter 60 which is substantially perpendicular to the surface of the skin. This vibratory motion of the comb 62 causes the hairs of the beard to be forced through the apertures 63 and be clipped off close to the skin by the cutter 60. In this way a much closer shave may be obtained than with the ordinary electric shaver.

It is to be understood that the comb may be oscillated axially instead of vertically as shown or may be given a movement which combines vertical, axial and pivotal movement as desired to facilitate the passage of the beard through the apertures therein and the cutting thereof.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

1. In an electric shaver, a comb member having apertures through which the hairs are adapted to extend, an oscillating cutter cooperating therewith, an electric motor, and means actuated by said motor to cause oscillatory movement of said comb member and of said cutter at different rates of speed.

2. In an electric shaver, a comb member having apertures through which the hairs are adapted to extend, an oscillating cutter cooperating therewith, an electric motor, and means actuated by said motor to cause oscillatory movement of said cutter at a given rate of speed and to cause oscillatory movement of said comb at a slower rate of speed.

3. An electric shaver of the type having a motor and a cutting member comprising an oscillating knife driven thereby, a comb positioned over said cutting member and provided with apertures to receive the hairs for cutting by said knife, said comb being circular in cross section and being pivotally mounted for limited oscillatory movement about its axis, and means actuated by said motor for imparting said oscillatory movement to said comb.

4. The invention set forth in claim 3 in which the motor actuated means imparts oscillatory movement to said comb at a rate slower than that of said cutting member.

5. An electric shaver of the type having a motor and a cutting member driven thereby, a comb positioned over said cutting member and provided with apertures to receive the hairs for cutting, said comb being mounted for limited vertical oscillatory movement, and means actuated by said motor for imparting said oscillatory movement to said comb.

6. The invention set forth in claim 5 in which the motor actuated means imparts an oscillatory movement to said comb at a slower rate than that of said cutting member.

7. In an electric shaver of the type having a motor and a cutting member driven thereby, a comb positioned over said cutting member and provided with apertures to receive the hair for cutting, said comb and cutting member each being mounted for transverse movement, and means actuated by said motor for imparting different oscillatory transverse movements to said comb and to said cutting member.

JOHN HAYS HAMMOND, JR.

DISCLAIMER
